C. S. WAGNER

RADIATING ELEMENT FOR GAS HEATERS

Filed Oct. 21, 1926

FIG. 1.

FIG. 2.

Inventor

C. S. Wagner

By C. S. Wagner

Attorney

UNITED STATES PATENT OFFICE.

CHARLES S. WAGNER, OF FORDS, NEW JERSEY, ASSIGNOR TO GENERAL CERAMICS COMPANY, OF KEASBY, NEW JERSEY, A CORPORATION OF NEW JERSEY.

RADIATING ELEMENT FOR GAS HEATERS.

Application filed October 21, 1926. Serial No. 143,254.

The invention relates to a new article of manufacture comprising a radiating element for gas heaters in the form of a rod or stick of porous refractory earthy material, such as ceramic clay, having a roughened and indented surface, preferably in the form of alternate grooves and ridges, with the marginal edges of the grooves roughly serrated or generally erose, so that, when the elements are heated by an impinging gas flame, the roughened surface will develop various and varying degrees of incandescence as compared with the body thereof, thereby producing not only a pleasing effect, simulating burning coals, but also increasing the radiating efficiency of the element.

The invention is illustrated in the accompanying drawings, in which:—

20 Fig. 1 is a perspective view of one of the elements.

Fig. 2 is a horizontal cross section thereof.

Referring to the drawings, 1 represents the body of the element, which is preferably in the form of a rod or generally cylindrical stick of refractory earthy material, such as ceramic clay, or the like, which may be conveniently formed by extruding the material in a plastic state through a suitable die and cutting the extruded material into the desired lengths to form the sticks or rods. It is also preferred that the body of the stick or rod be porous and, to effect this condition, a suitable amount of combustible material, such as sawdust, or the like, is admixed with the plastic material and is burned away during the process of firing or burning the sticks or rods.

The surface of the rods or sticks is roughened and pitted throughout to form projections and indentations, and is also preferably provided with alternating longitudinal grooves and ridges 2 and 3, with the marginal edges of the grooves roughly and irregularly serrated or erose, as at 4, and the superficial surface of the grooves and ridges roughened and indented, these effects being produced by notching or irregularly serrating the face of the die of the extrusion machine through which the ceramic material is

forced, the projections on the face of the die causing the marginal edges of the grooves and the surface of the rod or stick generally to be torn, roughened and indented, which condition is retained and fixed permanently in the finished article, after the same has been fired.

The sticks cut to proper length are assembled in any desired relation in a gas heater, and may even be loosely arranged in a grate 60 or heater like loose sticks or logs of wood, so that, when the gas flame, or the products of combustion thereof, impinge the sticks, the latter become highly heated and will radiate the heat. While the body of the rods 65 or sticks acquire a certain degree of incandescence, which is more or less uniform, the erose marginal edges of the grooves and ridges will become more highly incandescent and will vary in the degree of incandescence, 70 as will the roughened and pitted superficial surface of the rod or stick, thereby not only producing a highly luminous effect, but also materially increasing the radiating effect of the rod or stick as a whole.

What I claim is:

1. A radiating element for gas heaters, comprising a rod of porous refractory earthy material having an erosely roughened surface.

2. A radiating element for gas heaters, comprising a rod of porous refractory earthy material having a longitudinally grooved and roughened surface.

3. A radiating element for gas heaters, comprising a rod of refractory earthy material having irregularly spaced longitudinal ridges and grooves with roughened surfaces and irregularly notched marginal edges.

4. A radiating element for gas heaters, comprising a rod of refractory earthy material having longitudinal grooves with erose marginal edges.

5. A radiating element for gas heaters, comprising a rod of refractory earthy material having a roughened and pitted surface and longitudinal grooves with erose marginal edges.

In testimony whereof I affix my signature.
CHARLES S. WAGNER.
